UNITED STATES PATENT OFFICE.

JACOB MARTIN, OF BROOKLYN, NEW YORK, ASSIGNOR TO LANDAU ECONOMIC SYPHON COMPANY, OF SAN FRANCISCO, CALIFORNIA, A CORPORATION OF CALIFORNIA.

SIPHON.

No. 901,979.

Specification of Letters Patent.

Patented Oct. 27, 1908.

Application filed November 5, 1907. Serial No. 400,780.

To all whom it may concern:

Be it known that I, JACOB MARTIN, a citizen of the United States, and residing at Brooklyn, in the county of Kings and State 5 of New York, have invented certain new and useful Improvements in Siphons, of which the following is a specification, such as will enable those skilled in the art to which it app pertains to make and use the same.

- 10 This invention relates to siphons, and the object thereof is to provide improved means for regulating the pressure in vessels of this class, or to prevent the increase of said pressure beyond a predetermined point.
- 15 The invention is fully disclosed in the following specification, of which the accompanying drawing forms a part, in which the separate parts of my improvement are designated by suitable reference characters in 20 each of the views, and in which:

Figure 1 is a side view of a siphon provided with my improvement; and, Fig. 2 a partial section on the line 2—2 of Fig. 1.

In the drawing forming part of this specification, I have shown, at *a* the top of a siphon or similar vessel to which is secured the usual neck member *b* provided with a discharge spout *c* which communicates therewith at one side thereof in the usual manner, 25 and, in the practice of my invention, I connect with one side of the neck member *b* below the discharge spout *c* a pressure regulating device *d*. The pressure regulating device *d* comprises a port *d²* inclosed by a 30 threaded neck *d³* provided with a threaded cap *b⁴*, and placed in the neck *d³* is a valve *d⁵* adapted to close the port *d²*, and between which and the cap *d⁴* is a spring *d⁶* designed to hold the valve *d⁵* upon its seat and to 35 close the port *d²*. The neck *d³* is also provided with a side port *d⁷* which is located in such manner that it cannot be closed by the cap *d⁴*, and the pressure of the spring *d⁶* on the valve *d⁵* may be regulated at any time by 40 turning the cap *d⁴*. If the said pressure is to be increased the cap *d⁴* is turned to the right, 45

and if it is desired to lessen said pressure, the cap *d⁴* is turned to the left and, in this way, the pressure in the siphon or vessel *a* may be regulated as will be readily understood, it 50 being apparent that whenever said pressure increases beyond a predetermined point the valve *d⁵* will be opened thereby and the over-pressure exhausted through the ports *d²* and *d⁷*.

It is a well known fact that siphons or other vessels of this class are frequently burst or destroyed by reason of the increase of pressure therein, but by means of my improvement this difficulty may be ob viated; and although, I have shown a pressure regulator or exhaust of specific form and construction, it will be apparent that various changes therein and modifications thereof may be made, within the scope of the 55 appended claim, without departing from the spirit of my invention or sacrificing its advantages.

Having fully described my invention, what I claim as new and desire to secure by Letters Patent, is:

A siphon or similar device, the neck of which is provided with the usual discharge spout and a pressure exhaust device connected with the neck below the discharge 75 spout, said device consisting of a port or passage in the side of the neck, an outwardly directed screw-threaded tubular casing inclosing said port or passage and provided adjacent to said neck with an outlet, a threaded 80 cap screwed onto said casing, a valve within said casing for closing said port or passage, and a spring placed between said cap and said valve.

In testimony that I claim the foregoing as 85 my invention I have signed my name in presence of the subscribing witnesses this 30th day of October 1907.

JACOB MARTIN.
